United States Patent Office.

RICHARD SMITH, OF PHILADELPHIA, PENNSYLVANIA, ASSIGNOR TO
MACKELLAR, SMITHS & JORDAN.

Design No. 4,267, dated July 26, 1870.

DESIGN FOR TYPE.

The Schedule referred to in these Letters Patent and making part of the same

I, RICHARD SMITH, (assignor to MacKellar, Smiths & Jordan,) of the city and county of Philadelphia, Pennsylvania, have invented and produced a new and original Design for Printing-Type, of which the following is a specification.

The nature of my design is fully represented in the accompanying typographic impressions, to which reference is made.

I claim as my invention—
The design for a printing-type, as shown.
RICHARD SMITH.
